UNITED STATES PATENT OFFICE.

PHILIP J. HARRAH, OF BLOOMFIELD, INDIANA.

LIFTING-JACK.

1,307,968.

Specification of Letters Patent. Patented June 24, 1919.

Application filed May 6, 1918. Serial No. 232,910.

To all whom it may concern:

Be it known that I, PHILIP J. HARRAH, of Bloomfield, in the county of Greene and State of Indiana, have invented certain new and useful Improvements in Lifting-Jacks; and I do hereby declare the following to be a full, clear, and exact description of the invention, such as will enable others skilled in the art to which it appertains to make 10 and use the same.

In this invention my object is to improve that class of devices in which the lowering action as well as the lifting movement is effected step by step. Broadly stated I employ a standard having a plurality of perforations and a pair of runners movable on the standard. Each of the runners is provided with a spring actuated pin adapted to be projected into the perforations. The 20 operating lever mechanism causes the runners to alternately constitute the fulcrum point and the weight. A reversing plate effects the alternate movement of the runners in the opposite direction.

25 In the accompanying drawings, Figure 1 is a side elevation, Fig. 2 a vertical section and Fig. 3 a detail of the reversing plate. Fig. 4 is a fragmentary view in side elevation opposite to Fig. 1.

30 I have shown an upright standard 1 mounted upon a suitable pedestal and formed with a vertical series of perforations 2. These extend entirely through the standard so that it may be reversed when the 35 surfaces surrounding the perforations become worn. 3 and 4 show the runners comprising sleeves preferably rectangular in cross section to correspond to the formation of the standard. The operating lever 5 is of bell-crank formation at its inner end as at 40 5^a where it is shown fulcrumed to the upper runner 4 as at 6. The runners are connected by a vertically disposed pitman 7 fulcrumed to the lower runner 3 as at 8 and to the bell- 45 crank portion of the lever 5 as at 9. Thus the pitman operates as a movable fulcrum in the lifting action and it and the lever 5 constitute a toggle link mechanism. When the runner 3 is fixed, the fulcrum of the lever 50 action is at 9 and when the runner 4 is fixed the fulcrum is at 6. The runner 4 is shown provided with the usual foot or step 10.

I have shown the lower runner 3 apertured to receive a pin 12 having a cross arm 55 13 and having its outer extremity movable in a bearing formed by a bracket 14 which

may be cast integrally with the runner. A spring 15 is shown coiled upon the pin and bears at one end against the cross arm and at the other end against the bracket. The 60 tendency of the spring is to project the pin inward and into one of the perforations 2 of the standard when the pin and a perforation are in alinement. At its outer extremity the pin is beveled at its upper side 65 as at 16. By "upper side" I have reference to the side facing the top of the standard when the device is used in an upright position. The purpose of the bevel is that when a lifting force is exerted upon the runner 70 to draw it toward the top of the standard the beveled surface 16 will allow the pin to slide over the wall of the perforation in which it has been seated. The straight or uninterrupted formation at the opposite 75 side of the pin, as at 17, prevents the pin withdrawing when the weight is bearing upon the runner. When the runner is to be moved downward it is necessary to effect the positive withdrawal of the pin.

80 The runner 4 is equipped with a pin 18, cross arm 19, bracket 20, spring 21 and beveled extremity 22 similar to the parts above described with relation to runner 3.

The perforations in the standard are so 85 disposed that in the movement of the runners the pins 12 and 18 will not both be projected into the perforations at the same time. When one pin is projected the other pin is resting or moving on the surface between two of the perforations.

From what has thus far been said it will be understood that with the pin 12 of runner 3 seated in a perforation as in Fig. 2, the downward movement of the lever 5 will lift 95 the runner 4, the weight being at point 6 and the fulcrum of the toggle link mechanism at 9. Runner 4 is elevated until its pin 18 snaps into a perforation. Raising the lever 5 shifts the fulcrum to the point 6 100 and the pitman 7 elevates the runner 3 until its pin 12 snaps into a higher perforation. This action is continued during the elevation of the jack.

The reversing mechanism is shown consisting of a plate 23 bridging the space between the two runners and having appropriate bearing spaces provided by the brackets 14 and 20. This plate is adapted to be longitudinally movable and is under the tension of a spring 24 shown seated in a housing 25 formed in the upper runner 4 and

bearing against a lug 26 formed on the plate. The plate is shown formed with upper and lower cam surfaces 27—28 so disposed as to be in operative relationship to the cross arms 19 and 13. The reversing plate is shown formed with a curved upper extremity 29. A cam switch 30 is pivoted on the face of the runner 4 within a slotted depending portion 31 of the reversing plate. 6 In the lifting action the reversing plate is in the position shown, that is, elevated against the tension of its spring. When the switch 30 is turned downward so that its cam surface permits the plate 10 23 to drop under the tension of spring 24, the cams 27, 28 will be brought close to their respective cross arms 19 and 13. The subsequent operation of the lever 5 will cause the cross arms to ride up on the 20 cam surfaces and effect the positive withdrawal of the pins so as to permit the downward travel of the runners in step by step action. In this manner the toggle link mechanism which previously only permitted of a 25 raising action now allows of a lowering of the parts. By forming the standard with perforations extending entirely through its thickness it may be reversed so that the pins of the runners will operate on one or the 30 other of its sides. After some use on one side, the left as in Fig. 2, for instance, the walls around the perforations may become worn by the action of the pins. The standard may then be turned so that its right 35 side will receive the pins. This prolongs the term of usefulness of the standard in addition to insuring ample bearing surfaces in which the pins are supported when seated.

The essential elements of my invention 40 are adapted as well for wire stretching as for wagon jacks.

I claim as my invention:

1. A lifting jack comprising a standard having a plurality of perforations extending 45 entirely therethrough, a pair of runners movable on said standard, a spring actuated

pin carried by each of said runners for alternately entering said perforations to constitute a fixed stop while the other runner is advancing, a lever fulcrumed to one of said runners, and a pitman connecting said lever with the other runner. 50

2. In a lifting jack, a standard having perforations, a pair of runners having pins adapted to engage said perforations, means for projecting and withdrawing the pins, means for alternately advancing one of said runners while the pin of the other runner is projected into one of said perforations, and a reversing element having means for controlling the projection and withdrawal of said pins to reverse the direction of travel of said runners. 55 60

3. In a lifting jack, a standard having perforations, a pair of runners, a spring actuated pin having a cross arm and carried by each of said runners adapted to be projected into said perforations, means for alternately advancing one of said runners while the pin of the other runner is projected into one of said perforations, and a reversing plate having cam surfaces adapted 65 70 to engage said cross arms to alternately withdraw said pins and reverse the direction of movement of the runners. 75

4. In a lifting jack, a standard having perforations, a pair of runners, spring actuated pins on said runners having cross arms and beveled at one side of their extremities, means for alternately advancing one of said 80 runners while the pin of the other runner is projected into one of said perforations, a reversing plate having cam surfaces adapted to engage the cross arms to alternately withdraw said pins and reverse the direction 85 of movement of the runners, and means for maintaining said reversing plate ineffective during the action of raising said runners.

In testimony whereof I have signed this specification.

PHILIP J. HARRAH.
